UNITED STATES PATENT OFFICE.

FRANCIS G. CRONE, OF BUFFALO, NEW YORK.

MIXING UNIT FOR GASES.

1,205,436.

Specification of Letters Patent.

Patented Nov. 21, 1916.

Application filed April 22, 1914. Serial No. 833,650.

To all whom it may concern:

Be it known that I, FRANCIS G. CRONE, a citizen of the United States of America, and a resident of the city of Buffalo, county 5 of Erie, and State of New York, have invented certain new and useful Improvements in Mixing Units for Gases, of which the following is a full, clear, and exact description.

10 My invention relates generally to mixing units, and has for its principal object to provide a device which will more thoroughly mix the fuel and air and thus produce a more perfect combustion.

15 Another object of my invention has been to provide a device which may be used in connection with gas burners to improve the combustion and to prevent back firing.

My device comprises a plurality of members 20 so formed and arranged as to provide a plurality of passage ways through which the products of combustion are passed. By passing the products of combustion through these passage ways, the burning point is 25 some distance from the mixing chamber and thus back firing of the flame is effectively prevented.

Reference is to be had to the accompanying drawings, forming part of this specification, in which like characters of reference indicate like parts throughout the several views, of which:

Figure 1 is a perspective view of a rectangular-shaped unit, composed of a number 35 of members disposed one above the other. Fig. 2 is a plan view of a unit formed of circularly-shaped rings instead of flat plates. Fig. 3 is a sectional view of the same and is taken on line 3—3 of Fig. 2.

40 Fig. 4 is a front elevation of a sector-shaped furnace gas burner embodying my invention. Fig. 5 is a plan view of the same, partly broken away. Fig. 6 is a front elevation of a modified form of unit. Fig. 7 is a sectional view of a 45 elevation taken through the center line of a furnace which has been provided with burners embodying my invention. Fig. 8 is a plan view of a burner in which the circularly-shaped units are used.

50 My device comprises units 10, which are preferably formed of cast material, and are each provided on one surface with a plurality of corrugations or grooves 11 and on the opposite side with a smooth, flat surface. In the circularly-shaped unit shown in Figs. 2 and 3, the members 10 are made in

the form of rings with the corrugations or grooves 11 formed on the outer circumference and with the smooth surface on the inner circumference. These rings are preferably cast with tapered surfaces so that they may be easily assembled and when so assembled, are disposed one within the other.

In the gas burner shown in Figs. 4 and 5, 65 the bottom of the burner box 12 is preferably provided with a plurality of corrugations or grooves 13, so that when the units 10 are placed within the box, the smooth surface of the lower unit will contact with 70 the ridges on the bottom of the box and form an additional number of passage ways. After the members 10 have been placed in the box, a cover 14 is placed over the top and bolts 15 pass through the cover 14, members 10 and bottom of the box, thus securely holding the burner parts together. The box 12 is thus closed on all sides, except the face of the same where combustion occurs. The cover 14 is provided at each end with 75 a spacing rib 16, which acts to keep the burner at a proper distance from the firepot when placed in the furnace, as clearly shown in Fig. 7. The burner cover is also provided with a screw-threaded aperture by 80 which the mixing pipe 17 may be attached to the burner. The bottom of the box 12 is also provided with a screw-threaded aperture directly beneath the screw-threaded aperture in the cover 14 by means of which 85 the mixture may be fed to the burner from the upper surface or the lower surface, as conditions may require. Obviously, when the mixing pipe 17 is attached to the cover 14 of the burner, the aperture in the lower 90 side of the box 12 is closed by means of a plug. The members 10 are placed flush with the front surface of the burner and do not extend back to the rear side of the box, thus providing a chamber 18 in which the 95 mixture enters before it passes out from the plurality of passage ways formed by the members 10. As shown in Fig. 7, preferably four of these burners are used in the furnace, and each is provided with a separate mixing pipe 17, air mixers 28 and gas valves 19. These valves 19 supply gas to the mixers from the gas pipe 20. As shown in this figure, the mixing pipes 17 are passed through the coal feeding opening 21 of the 100 furnace and thence down to the burners. If, however, local conditions do not permit 105

these pipes to be arranged in this manner, they may be passed through the ash opening 22 and connected to the lower side of the gas burners.

5 In Fig. 6, I show a modified form of unit where alternate corrugated and smooth members are used. In this figure, the members 23 are provided with corrugations or grooves 24 on opposite sides, and when arranged in a unit a flat member 25 is alternately disposed between the corrugated members, thus forming the passage ways. It is obvious that this modification may also be embodied in a circularly-shaped unit 10 similar to that shown in Figs. 2 and 3.

15 In Fig. 8, I have shown a ring gas burner composed preferably of two parts 26 and 27, each being provided with a mixing pipe 17. This burner is provided on its upper 20 surface with a plurality of cylindrical apertures, in each of which is arranged one of the circularly-shaped units shown in Figs. 2 and 3.

25 Obviously, if desired, the ring units shown in Figs. 2 and 3, may be provided with the corrugations on the inner surface instead of the outer, or my units may be made in dif-

ferent shapes to conform to local conditions. These and many other modifications of the details herein shown and described may be 30 made without departing from the spirit of my invention or the scope of the appended claim.

Having thus described my invention, what I claim is:

35 A mixing unit for gases comprising, a solid, annularly tapered central member having an external corrugated surface, an annular member having a smooth, tapered, interior surface and a tapered, exterior, corrugated surface disposed around and in contact with said central member, and an annular, exterior member having a tapered, smooth, inner surface and a corrugated outer surface, said annular, exterior member being disposed around said annular member and in contact with the corrugations thereof.

40 In testimony whereof, I have hereunto signed my name in the presence of two subscribing witnesses.

FRANCIS G. CRONE.
